UNITED STATES PATENT OFFICE.

JOHN CONWAY, OF EAST TOLEDO, OHIO.

FRUIT-JAR.

1,146,137.

Specification of Letters Patent. Patented July 13, 1915.

Application filed February 13, 1915. Serial No. 7,945.

To all whom it may concern:

Be it known that I, JOHN CONWAY, a citizen of the United States, (post-office address East Toledo,) residing in the county of 5 Wood and State of Ohio, have invented certain new and useful Improvements in Fruit-Jars, of which the following is a specification.

My invention relates to improvements in 10 fruit jars, and more particularly to an improved cover and cover clamping and securing device for such jar.

The primary object of my invention is to 15 provide a generally improved jar cover clamping and securing device which may be readily attached or applied to the jar or container and when so applied will not only effectively seal the contents, but on the other hand, may be readily removed or detached 20 without impairing or damaging any of the parts so that the improved cover attaching or clamping device may be used over and over as desired.

A further object is the provision of a 25 cover clamping and securing device of exceedingly simple, cheap, and efficient construction, which may be readily and quickly applied to any ordinary fruit jar or container having an externally threaded top or neck.

A still further object is the provision of 30 an improved bearing ring for coöperating with the cover clamping yoke, said bearing ring being adapted to be mounted upon and 35 to coöperate with an ordinary externally beaded and threaded neck of an ordinary jar or container.

A still further object is the provision of 40 an improved cover clamping device adapted 45 to eliminate friction between the friction bearing surfaces of the adjacent parts in the act of attachment or detachment of the same thereby more securely sealing the parts in attachment as well as providing for the more ready removal of the cover from the jar or container.

With the above mentioned and other ends 50 in view, the invention consists in the novel construction, arrangement, and combination 55 of parts, hereinafter described, illustrated in some of its embodiments in the accompanying drawings, and particularly pointed out in the appended claims.

Referring to the drawings forming a part

of this specification, Figure 1, is a top plan 55 view of the improved cover and cover clamping device in its closed or sealed position as applied to a jar or container of ordinary form. Fig. 2, a side elevation of the same. Fig. 3, a side elevation, the improved cover 60 and attaching or clamping ring being in section as indicated on line 3—3 of Fig. 1, the neck of the jar being in side elevation and partly broken away for the purpose of illustrating the purpose of the externally beaded 65 part. Fig. 4, a central sectional view of the lid or cover provided with a slightly modified form of lid retaining yoke the latter being provided with a supplemental lid and yoke clamping device. Fig. 5, a detail side 70 elevation of the form of yoke shown in Fig. 4.

Similar numerals of reference designate 75 like parts throughout all the figures of the drawings.

The jar or container body 1, in the present instance, is provided with an externally beaded and threaded neck 2, said neck 2, in the present instance, having a circumferentially extending beading 2^a, and an inclined 80 or convoluted rib 2^b, forming the threaded portion, such as frequently employed on an ordinary jar for the reception of an ordinary threaded top or cover. As a means of eliminating friction in the attachment or detachment of the improved device in connection with an ordinary jar such as described, as well as adapting the device to such jar for forming a better sealing contact between the parts, an improved attaching and clamping 85 ring 3, is provided, said ring 3, being formed of suitable metallic material and being provided about its inner periphery with a convoluted rib or thread 3^a, similar in form and length to the rib 2^b, of the bottle neck, and 90 being adapted to coöperate therewith in attaching or detaching the improved ring 3, and as a means of leveling and supporting the ring 3, with respect to and above the beading 2^a, the ring 3, is provided about its 95 lower edge with a series of lugs or supports 3^b, these supporting lugs 3^b, being adapted to coöperate with the beading 2^a, for holding the ring in proper position when drawn upon the rib 2^b, of the bottle, or jar 1.

The clamping and attaching ring 3, is provided with a pair of externally arranged flanged inclines 3^c, said flanges or inclines

3°, being inclined in the same general direction with the ribs or threads 2^b, and 3^a, so that when the lid clamping and retaining yoke, hereinafter described, is drawn up in 5 coöperation with the inclines 3°, the ring will be held in fixed relation to the externally beaded and threaded neck.

The improved lid, or cover 4, is provided with a depending rim or flange 4^a, adapted 10 to fit within the bottle neck and is provided with a radially extending horizontal flange 4^b, adapted to extend over and cover the upper edges of the threaded neck, said rims or flanges 4^a, and 4^b, forming a convenient 15 seat for a gasket 5, of rubber interposed between the flanged or rim portions 4^a, of the lid or cover and the top of the jar, to securely seal the lid when clamped down by the improved lid retaining yoke to be now 20 described.

The improved lid retaining yoke 6, is adapted to span the lid or cover 4, and is preferably provided at its center with a bearing head 6^a, the latter being preferably provided with a centering stud 6^b, adapted to be seated within and to coöperate with a similarly shaped recess or depression 4^c, in the lid or cover. The yoke 6, terminates at its ends in depending arms 6^c, adapted to extend below the sides of the lid and terminating in inwardly extending lugs 6^d, which latter are adapted to extend below or take over and engage with the inclines 3°, in the act of securing the lid in position and sealing the same by the circumferential movements of the lid retaining yoke in coöperative relation with the inclines 3°.

As a still further means of clamping and sealing the lid or cover, as lightly modified 40 form of yoke as shown in Figs. 4 and 5, may be provided, in which instance the yoke 6, is provided with a depending pin 6^e, adapted to carry or form a bearing for the lid and yoke clamping device, consisting, in the 45 present instance, of a rotatably mounted disk shaped member 7, provided with oppositely extending inclines 7^a, at its top and about its outer periphery and provided also with an outwardly extending operating 50 handle 7^b. By moving the handle 7^b, to the left it is obvious that as the inclines 7^a, ride under the yoke 6, the latter will be caused to coöperate with the disk shaped member 7, and the subjacent lid or cover 4, causing the 55 latter to be pressed, as well as compressed upon the gasket 5, with great force, thereby securely sealing the lid or cover upon the jar or container in an obvious manner.

By reason of the above construction, it 60 will be obvious that friction is eliminated from the adjacent coöperating parts and that the parts may not only be securely sealed in the act of drawing up, but that the parts may be readily removed in the act of 65 opening or unsealing the jar cap and that an

exceedingly sanitary jar cover and attaching and clamping device is provided.

From the foregoing description, taken in connection with the accompanying drawings, the operation and advantages of my invention will be readily understood.

Having thus described some of the embodiments of my invention, what I claim and desire to secure by Letters Patent, is,—

1. In a fruit jar, the combination with a 75 jar provided with an externally beaded neck having a convoluted rib above said beading; of an attaching ring having a similarly shaped internally arranged convoluted rib coöperating with said first mentioned rib, 80 said ring having depending supports resting on said beading and provided with oppositely arranged inclines extending in the general direction of said convoluted ribs.

2. In a fruit jar, a jar provided with an 85 externally beaded neck, said neck being provided with a convoluted rib arranged above the plane of said beading, and an attaching ring resting on said beading and provided about its inner and outer peripheries with 90 ribbed inclines extending in the general direction of said convoluted rib and adapted to coöperate therewith.

3. A fruit jar, comprising a jar body provided with a circumferentially beaded neck 95 having a convoluted rib, a ring provided about its inner periphery with a similarly shaped convoluted rib coöperating with said rib of said neck and having depending supports resting on said beading said ring being provided with diametrically opposite externally arranged inclines extending in the general direction of said convoluted ribs, a lid mounted on said neck and having a depending rim or flange taking within said 100 neck, and a lid retaining yoke having inwardly extending lugs engaging with said inclines.

4. A fruit jar, comprising a jar provided with an externally beaded neck having a 110 convoluted rib, a ring threaded thereon and resting above said beading, said ring being provided with externally arranged flanges inclined in the general direction of said convoluted rib, a lid mounted on said neck, a 115 lid retaining yoke having inwardly extending lugs normally engaging with said flanges, and a disk shaped member provided with oppositely extending inclines interposed between said yoke and lid, said disk shaped member being rotatably mounted and provided with a radially extending handle.

5. A fruit jar, comprising a jar provided with a circumferentially arranged beading, and having a neck portion provided with a 125 convoluted rib arranged above said beading, a clamping and attaching ring provided about its inner periphery with a similarly shaped convoluted rib coöperating with said convoluted rib of said neck and said cir-

cumferentially arranged inclines, a lid or cover mounted on said bottle neck above said ring, and a lid retaining yoke extending across said lid or cover and provided
5 with depending arms terminating in inwardly extending lugs in engagement with said oppositely arranged inclines.

In testimony whereof I have affixed my signature in presence of two witnesses.

JOHN CONWAY.
